UNITED STATES PATENT OFFICE.

HENLEY C. CASKEY, OF SIOUX RAPIDS, IOWA.

CORN-HUSKER.

1,197,341.

Specification of Letters Patent. Patented Sept. 5, 1916.

Application filed March 31, 1916. Serial No. 87,975.

To all whom it may concern:

Be it known that I, HENLEY C. CASKEY, a citizen of the United States, and a resident of Sioux Rapids, in the county of Buena Vista and State of Iowa, have invented a certain new and useful Improvement in Corn-Huskers, of which the following is a specification.

One of the principal objects of my invention is to provide an improved hook corn husker, having means for automatically keeping the hook free of kernels and unentangled with shreds or fibers of the corn husks, disadvantages commonly accruing to hook corn huskers in general.

A further object of my invention is to provide an improved corn husker in which a spring actuated plunger is arranged for automatically keeping the hook clear of encumbrances.

A further object is to provide an improved corn husker of the class described, which will be extremely simple, durable, efficient in operation, and inexpensive to manufacture.

With these and other objects in view which will become apparent as the description proceeds, the invention resides in the construction, combination, and arrangement of parts hereinafter more fully described and claimed, and illustrated in the accompanying drawing in which like characters of reference indicate like parts throughout the several figures, of which—

Figure 1 represents a view in perspective of a corn husker constructed according to my invention, showing the same as in position on an operator's hand. Fig. 2 represents a view in perspective of the husker removed. Fig. 3 represents a view in section taken on the plane indicated by the line 3—3 of Fig. 1. Fig. 4 represents a view in section taken on the plane indicated by the line 4—4 of Fig. 1.

Referring more particularly to the drawing, 5 represents a strap or band of preferably soft pliable material, such as leather, heavy canvas, or the like, which is designed to fit about the under side of the palm and wrist at the juncture of the hand with the wrist, in the manner shown in the drawing. Near one corner the band has a spur 6 which fits around underneath the thumb at its base. A metallic plate 7 is riveted or otherwise suitably secured to the band 5, and this plate is so shaped as to conform with the contour

of the hand at the base thereof. The plate has an arm 8 extending up around the thumb, and a spur 9 which overlies the spur 6 of the band and fits around under the thumb. A strap 10 suitably riveted or otherwise secured to this spur 9, passes over the top of the thumb at its base, extends through a slot 11 provided adjacent the outer end of the arm 8, and is returned across the back of the hand to engage a buckle 12 carried on the portion 13 of the band 5 which fits around outside the base of the hand at the wrist. A second strap 14, connecting the end portions of the band 70 across the top of the hand, completes the means for securing the device in place. It may here be noted that, by pulling on the strap 10, the device will be tightened around the thumb to assume a snug fit and at the same time will be drawn closely around the hand.

Carried by the plate 7 at the base of the spur 9, in position to point back toward the wrist, is a metal hook 15 which lies substantially parallel with the adjacent portion of the plate. The hook is provided with a shank portion 16 lying substantially at right angles with the hook and plate and which is pivotally mounted by means of 85 laterally extending lugs in bearings 25 stamped out from the plate. The shank 16 rises from a base portion 26 which occupies an opening provided in the plate 7, said base lying flush with the plate. A flat leaf 90 spring 27 which underlies the spur 9, is riveted or otherwise suitably secured as at 28 to the base 26, the opposite end of the spring being fastened to the plate 7 by one of the fastenings used in securing the housing 20, hereinafter described, in place. The details of the operation of shucking corn by means of a hook are well known to persons versed in the art, and it is therefore unnecessary to recite them here. It has been 100 found in many instances that kernels of grain become lodged underneath the husking hook, and interfere materially with the proper operation of the same, and, it is to obviate this disadvantage that I have pivoted the hook in my invention and provided it with a spring, as already set out, which, in normally maintaining the hook in proper position relatively to the plate, at the same time allows the hook to give under excess 110 strain so that the kernels of grain will not lodge under the hook.

My invention further provides a means for continually keeping the hook clear of husks and other encumbrances, this means including a spring actuated plunger 17 positioned between the hook and plate for reciprocation longitudinally of the hook. The plunger is curved transversely having its concaved side facing the outer end of the hook. A rod 18 on the outer end of which the plunger is carried passes through an opening 19 in the hook shank 16 and, extending within a housing 20 carried on the plate, is engaged by the free arm of a wire or other suitable spring 21. This wire is coiled about the shank of one of the rivets employed in securing the housing in place, and has its opposite end bent over the adjacent edge of the plate 7 for anchoring the spring. The tendency of the spring is to force the plunger toward the outer end of the hook, so that, during the husking operation if any of the portions of the husks should become entangled or caught beneath the hook, thus forcing the plunger back out of normal position, the spring will, immediately the tension exerted by the husking operation is relieved, force the plunger out and thus clear the hook. In this manner the device operates automatically for keeping the hook at all times in condition to most efficiently perform its work.

The housing 20 serves to protect the spring mechanism and the inner portion of the plunger from injury and from any dust and dirt which might, in accumulating, interfere with the proper operation of the device. At its forward edge the housing abuts against the shank 16 of the hook, and is provided with spaced depending cups 22 between which the rod 18 is guided, and which serve to receive packing material 23 which may, if desired, be used in storing lubricant for the moving portions of the device. These cups may be formed integrally with the housing, or they may be fashioned of strips of material having portions suitably anchored in the housing as at 24. These cups serve to restrain the shaft or rod 18 to a certain path of reciprocation. Although I have described the preferred embodiments of my invention, I may desire to make such changes in the construction, combination, and arrangement of parts thereof, as do not depart from the spirit of the invention and the scope of the appended claims.

I claim:

1. In a corn husker, the combination of a plate, means for securing the same to the hand of an operator, a hook pivotally mounted on the plate, means controlling the hook normally maintaining it in substantially parallel relation with the plate and adapted to allow the hook to give under excess pressure, and means for automatically coöoperating with the hook as it gives for keeping the hook free of obstructions.

2. A device of the class described including a plate adapted to be secured to the hand of an operator, a hook carried by the plate and extending parallel therewith, a concaved plunger arranged between the hook and the plate and having its concaved face turned outwardly, a rod to which the plunger is secured, said rod being extended through an opening in the shank, a spring carried by the plate and having connection with the rod normally tending to move the plunger toward the outer end of the hook, a housing covering the spring and adjacent portions of the rod, cups carried by the housing between which the rod is guided, and a packing carried by the cups for retaining lubricant.

3. The herein described husking device including a plate adapted to be secured to the hand of an operator, a hook carried by the plate, a plunger arranged between the hook and plate, a shaft on which the plunger is carried, said shaft being extended through an opening in the shank of the hook, spring means engaging the shaft for normally tending to move the plunger up toward the outer end of the hook, and a housing covering the spring and adjacent portions of the shank.

4. The herein described corn husker including a band adapted to be secured to the hand of an operator, a plate carried by said band, a hook carried by the plate, a plunger arranged between the hook and plate, a shaft on which the plunger is carried, spring means for operating the plunger, said spring means being connected with the said shaft, and a housing covering the spring means and adjacent portions of the shaft for protecting them.

5. A device of the class described including a band adapted to be secured to the hand of an operator, a plate carried by said band, a hook arranged on the plate, a plunger arranged between the plate and hook, and spring means for operating the plunger whereby to normally force it toward the outer end of the hook, and means for protecting said spring means, consisting of a housing secured on the plate over the spring.

6. A device of the class described including a pliable band adapted to be secured to the hand of an operator, a metallic plate carried by said band, a hook arranged on the plate, a plunger arranged between the hook and plate, spring means for operating the plunger tending to move it toward the outer end of the hook, and means for housing said spring means.

7. A corn husker including a pliable band adapted to be secured to the hand of an operator, a plate carried by said band, a hook carried by the plate, a plunger arranged be-

5. 12. A corn husker including a plate, means for securing the same to the hand of an operator, a hook pivotally mounted on the plate and extending normally in parallel relation therewith, said hook being provided with a base portion lying within an opening provided in the plate, a leaf spring underlying the plate and secured at one end thereto, the opposite end of the leaf spring being connected with the base portion of the hook for retaining the hook in normal position, said spring adapted to allow the hook to give under excess pressure. 30 35 40
10. 13. A corn husker including a plate, means for securing the same to the hand of an operator, a hook pivotally mounted on the plate, spring means connected with the hook and plate for normally maintaining the former in substantially parallel relation with the plate, said spring means adapted to allow the hook to give under excess pressure, and a spring operated plunger arranged between the hook and plate and normally held toward the outer end of the hook. 45 50
15. 20. 25. 10. In a corn husker, the combination of a plate, means for connecting it to the hand of an operator, a husking hook carried by the plate, and reciprocatory means operating between the hook and plate for keeping the hook clear.
11. In a corn husker, the combination with a husking device including a plate and overturned hook, of reciprocatory means for automatically keeping the husking device clear.

Copies of this patent may be obtained for five cents each, by addressing the "Commissioner of Patents.
